UNITED STATES PATENT OFFICE.

SAM HERSH, OF CLEVELAND, OHIO.

HUMIDIFIER.

Original application filed January 23, 1925, Serial No. 4,334. Divided and this application filed October 15, 1925. Serial No. 62,526.

It is customary to provide in hot air furnaces air-humidifying means comprising a receptacle into which water may be introduced from the exterior of the furnace and from which this water may evaporate into the air current. As these receptacles are usually constructed at the present time, however, there is no way to close the opening through which the water evaporates into the air current and accordingly water being poured into the receptacle very often splashes over in appreciable quantity into the interior of the furnace where it produces obvious detrimental results. The principal object of my invention is to provide humidifying means of this type free from this objection. In the drawings accompanying this specification and forming a part of this application I have shown, for purposes of illustration, one form which my invention may assume. In these drawings:

Figure 1 is a fragmentary side elevation of a furnace embodying this illustrative form,

Figure 2 is a fragmentary horizontal section above the top of the receptacle taken on the line 2—2 of Figure 1, while

Figure 3 is a view similar to Figure 2 showing the cover in alternative position.

This present application is a division of my copending application Serial Number 4334 filed January 23, 1925.

The embodiment of my invention disclosed herein comprises a receptacle 46 supported by the base plate 12 of the furnace 13 in position extending through and closing an aperture 14 in the furnace wall 48, and provided with an open top 47 divided by the furnace wall 48 into an outer opening 50 through which water may be inserted into the receptacle 46 and an inner opening 49 through which water may evaporate into the air current within the furnace wall 48.

This receptacle 46 is provided with an ear 51 arranged to pivotally support a horizontally swinging cover 52 comprising an outer part 53 arranged to overlie and close the outer opening 50 and an inner part 54 arranged to overlie and close the inner opening 49 but disposed in relation to the outer part 53 in such manner that when the outer part 53 is in the position shown in Figure 2 exposing the outer opening 50 the inner part 54 is in position closing the inner opening 49, and when the inner part 54 is in the po-

sition shown in Figure 3 exposing the inner opening 49 the outer part 53 is in position closing the outer opening 50.

It will be apparent that this embodiment of my invention herein shown provides a closure for the inner receptacle opening and therefore provides means to prevent water splashing into the interior of the furnace. It will also be apparent that in the form of my invention herein illustrated this cover is connected to and correlated with the cover closing the outer opening in such manner that movement of the outer cover to expose the outer opening automatically closes the inner opening. It will therefore be obvious that the form of my invention herein disclosed accomplishes the principal object of my invention.

On the other hand, it will at the same time be obvious to those skilled in the art that the particular embodiment of my invention herein shown and described may be variously changed and modified without departing from the spirit of my invention or sacrificing the advantages thereof. It will therefore be understood that this disclosure is illustrative only and that my invention is not limited thereto.

I claim:

1. Means for humidifying the air of a hot air furnace, comprising a receptacle and a unitary cover for said receptacle comprising two leaves disposed generally in the same plane, pivoted about a common axis substantially perpendicular to said plane, and extending from said axis at such angles that either is in closed position when the other is in open position, one of said leaves being adapted to close that part of the receptacle lying within the furnace wall when said receptacle is in operative position and the other of said leaves being adapted to close that part of the receptacle lying outside the furnace wall when said receptacle is in such position.

2. Means for humidifying the air of a hot air furnace, comprising an open top receptacle and a unitary cover for said receptacle comprising two leaves disposed generally in the plane of the open top of said receptacle, pivoted about a common axis substantially perpendicular to said plane, and extending from said axis at such angles that either is in closed position when the other is in open position, one of said leaves

being adapted to close that part of the open top of said receptacle lying within the furnace wall when said receptacle is in operative position, and the other of said leaves being adapted to close that part of the open top of said receptacle lying outside the furnace wall when said receptacle is in such position.

3. Means for humidifying the air of a hot air furnace, comprising a receptacle and a unitary cover for said receptacle comprising two leaves disposed generally in the same plane, pivoted about a common axis substantially perpendicular to said plane and lying substantially in the wall of said furnace when said receptacle is in operative position, and extending from said axis at such angles that either is in closed position when the other is in open position, one of said leaves being adapted to close that part of the receptacle lying within the furnace wall when said receptacle is in operative position and the other of said leaves being adapted to close that part of the re-

ceptacle lying outside the furnace wall when said receptacle is in such position.

4. Means for humidifying the air of a hot air furnace, comprising an open top receptacle and a unitary cover for said receptacle comprising two leaves each arranged to close one of said openings, disposed generally in the plane of the open top of said receptacle, pivoted about a common axis lying substantially in the wall of said furnace when said receptacle is in operative position, and extending from said axis at such angles that either is in closed position when the other is in open position, one of said leaves being adapted to close that part of the open top of said receptacle lying within the furnace wall when said receptacle is in operative position, and the other of said leaves being adapted to close that part of the open top of said receptacle lying outside the furnace wall when said receptacle is in such position.

In testimony whereof I hereunto affix my signature.

SAM HERSCHE
